(57) **CLAIM**

An ornamental design for a display screen with graphical user interface for a timeline-video relationship presentation for alert events, as shown and described.

DESCRIPTION

This application is related to the following applications, which are all incorporated by reference in their entirety:

U.S. patent application Ser. No. 15/335,399, titled “Timeline-Video Relationship Presentation for Alert Events,” filed Oct. 26, 2016; and

U.S. patent application Ser. No 15/335,396, titled “Timeline-Video Relationship Processing for Alert Events,” filed Oct. 26, 2016.

The FIGURE is a front view of a display screen with graphical user interface for a timeline-video relationship presentation for alert events, showing our new design.

The broken lines showing a portion of a display screen, text, and other elements in the FIGURE are for illustrative purposes only and form no part of the claimed design.
